CLAIM

The ornamental design for a shirt as shown and described.

DESCRIPTION

FIG. 1 is a front view of a shirt showing our new design; FIG. 2 is a right side front perspective view thereof; and, FIG. 3 is a left side front perspective view thereof.

The broken lines immediately adjacent to the photographic area define the bounds of the claimed design and form no part thereof. The broken line showings of the unshaded areas within the photographic area form not part of the claimed design. The broken lines depicting the remainder of the shirt form no part of the claimed design.
